MAGAZINE PENCIL

John A. Leimer, Chicago, Ill.

Application August 10, 1936, Serial No. 95,233

15 Claims. (Cl. 120—14)

My invention relates to writing instruments and includes among its objects and advantages the provision of an improved magazine lead pencil.

5 An object of my invention is to provide a mechanical pencil in which a large number of sharpened writing points may be carried and sharpened writing points substituted for worn points by a simple manipulation of the pencil. 10 The invention also includes means for repelling writing points.

A further object is to provide a novel clutch for gripping the writing point projecting from the pencil, and in which the clutch is characterized by a shifting action longitudinally of the pencil only, thereby eliminating distortion of the clutch.

Another object is to provide a simple and efficient spring check and release cooperating 20 with the clutch to prevent writing points from falling out of the pencil when the clutch is adjusted to a releasing position.

A further object is to provide a clutch designed to secure effective gripping action on the writing point projecting from the pencil so as to prevent any free movement of the writing point.

In the accompanying drawing:

Fig. 1 is a perspective view of the pencil;

Fig. 2 is a sectional view along the line 2—2 of Fig. 1;

Fig. 3 is a sectional view along the line 3—3 of Fig. 2;

Fig. 4 is a sectional view along the line 4—4 of Fig. 3;

Fig. 5 is a view similar to Fig. 4 showing the pencil adjusted to eject the worn point;

Fig. 6 is a sectional view illustrating another adjustment of the pencil;

Fig. 7 is a sectional view along the line 7—7 of Fig. 2;

Fig. 8 is a sectional view along the line 8—8 of Fig. 3; and

Fig. 9 is a perspective view of the lead controlling mechanism illustrating the parts in separated relation.

In the embodiment selected to illustrate my invention, I make use of a pencil 10 having a tapered end 12 and a cap 14 housing an eraser 16. The barrel of the pencil comprises a tubular part 18 fixedly connected at 20 with an inner tube 22 slidably mounted within a tubular part 24 of the same diameter as the part 18 and normally positioned in end to end relation there- 55 with, as illustrated in Fig. 2.

The tapered end 12 comprises an extension of a tube 26 connected as a unit with the tubular part 24 through the medium of a coupling member 28. In Fig. 2, I illustrate the coupling member as having threaded relation at 30 with the tubular parts 24 and 26. The parts 24 and 26 are fixedly connected as a unit when drawn into firm end to end relation upon the coupling member. In lieu of the threaded connection between the parts 24, 26, and 28, part 26 may be made 10 as an integral part of the tube 24 and the sleeve 28 fixedly connected therein by any suitable manner of keying.

The coupling member 28 is in the nature of a sleeve having internal threads 32 for the reception of the threaded end 34 of a clutch head 36 fixedly connected within one end of the tube 22. Thus, the clutch head 36 may be disconnected from the sleeve 28 by turning the tubular part 18 about the longitudinal axis of the pencil 20 relative to the tube part 24.

Within the barrel of the pencil I mount a lead magazine 38 in the nature of a tube substantially coextensive in length with a pencil proper. One end of the lead magazine 38 is slidably 25 mounted within a tubular support 40 including a flange 42 welded about its periphery to the tubular part 18. I provide the tubular part 18 with internal threads 44 having threaded connection with a thimble 46 carrying the eraser 16. 30 The inner end of the thimble 46 includes a wall 50 carrying a pin 52 projecting into the lead magazine 38. The cap 14 encloses the eraser 16 illustrated in Fig. 2. This cap has frictional relation with the thimble 46.

In Figs. 2, 4, and 5, I illustrate the lead magazine 38 as containing a plurality of writing points 58, each having a sharp point 60. These writing points are arranged in end to end relation, but are of such diameter as to move freely of their own weight longitudinally of the magazine 38. The writing points 58 may comprise material such as is used in conventional lead pencils.

With a writing point 58 projecting from the pencil according to Figs. 2, 3, and 4, the writing point is held firmly by a clutch 62 cooperating with the tapered end 12 for clamping the writing point. When the clutch 62 is opened for releasing the writing point held thereby, the writing points are restrained from falling through the clutch end of the pencil by two fingers 64 of a spring check and release 66 mounted on the clutch.

Referring to Fig. 4, which illustrates the pen- 55

cil adjusted for writing purposes, the lead magazine 38 extends loosely through a sleeve 68 loosely mounted within the bore 70 of the clutch head 36. Sleeve 68 is flared at 72 to extend over one end of the clutch head 36 while the opposite end of the sleeve carries a thrust collar 74 having abutting relation with the opposite end of the clutch head.

The thrust collar 74 is fixedly connected with the sleeve 68 and carries a thrust arm 76 terminating in a projector point 78 which extends partly across the path of the writing points 58 in the magazine 38, as illustrated in Fig. 4. The thrust arm 76 may be shifted longitudinally of the pencil by unscrewing the clutch head 36 from the coupling member 28, at which time the thrust collar 74 and its thrust arm 76 together with the sleeve 68 may be retracted and advanced with the clutch head 36.

The spring check and release 66 is U-shaped in cross section with its flat reaches 82 lying against the flat sides 84 of the clutch 62. Each reach 82 carries an extension 86 which is bent to lie over the clutch 62, as indicated at 87 in Fig. 7 for connecting purposes. The spring check and release is made of resilient material so that the reaches 82 may be separated sufficiently to permit the spring check and release to be pressed over the clutch 62 for assembly purposes. In Fig. 9, the clutch 62 is shown to include a plurality of spaced resilient gripping elements 88 arranged to define a central opening 90 for receiving the writing points 58.

I fixedly connect one end of the lead magazine 38 with the clutch 62, which magazine is arranged in axial alignment with the opening 90 and communicates therewith for delivering the writing points 58 to the opening. The fingers 64 extend into the path of the writing points 58 through two of the spaces between the gripping elements 88 and comprise integral extensions of the side plates 82. The fingers are narrower than the spaces to permit free movement of the fingers 64, and the degree of gripping action of the fingers upon the writing points 58 is determined by the spring tension of the fingers.

In Fig. 9, one end of the coupling member 28 is shown provided with a wall 94 having a recess 96 constituting a race for the thrust arm 76. The thrust arm 76 moves freely longitudinally of the coupling member 28 but is restrained from relative rotary movement because of the guiding relation between the walls of the recess 96 and the thrust arm. The thrust arm is slidably positioned between two of the gripping elements 88, as illustrated in Fig. 7.

The two gripping elements 88 associated with the thrust arm 76 are spaced sufficiently far apart to freely accommodate the projector point 78 which is urged inwardly because of the spring tension in the thrust arm 76. Movement of the thrust arm 76 inwardly of the pencil is limited by reason of ledges 100 on the elements 88 which are positioned underneath the thrust arm 76. These ledges operate to prevent the thrust arm 76 from moving inwardly to a degree that might damage the writing points 58. Fig. 4 illustrates the thrust arm 76 at its maximum inward position. At the same time, the thrust arm 76 is free to move sufficiently far rearwardly of the pencil to bring the projector point 78 into propelling relation with the rear end of the writing point 58 in the clutch 62 (see Fig. 5).

In flattening the clutch at 84, I provide abutments 102 and 104 which have abutting rela-

tion with the ends 103 and 105, respectively, of the spring check and release 66. The close relation between the reaches 82 and the flat surfaces 84 prevents rotation of the spring check and release upon the clutch 62. Similarly, the clutch 62 is flattened at 106, and the flattened surface extends underneath the wall 94 to restrain the clutch 62 from any rotary movement within the pencil. Any clamping relation established between the clutch 62 and the tapered end 12 is brought about by shifting of the clutch longitudinally of the pencil. The clutch 62 is so mounted as to be properly aligned with the thrust arm 76 at all times.

While the fingers 64 and the thrust arm 76 lie within the contour of the clutch 62, the relation is such as to permit sufficient movement of the gripping elements 88 for constituting an effective grip on the writing points 58. Fig. 4 illustrates writing adjustment of the parts, at which time the projector point 78 lies behind the writing point 58 projecting from the pencil, and the gripping elements 88 are clamped firmly against the writing point because of the taper 12.

In substituting a new writing point 58 for the worn point 108 of Fig. 5, the clutch head 36 is unscrewed from the coupling member 28 and the tubular members 18 and 24 separated to the position of Fig. 5. In separating the member 18 from the member 24, the clutch head 36 is shifted rearwardly of the member 24, which moves the thrust arm 76 to a position where the cam surface 110 on the projector point 78 engages the end of the magazine 38 for lifting the projector point clear of the bore of the magazine.

With the parts adjusted according to Fig. 5, the clutch head 36 is arranged in abutting relation with the collar 112 fixedly mounted on the lead magazine 38. Coupling member 28 has abutting relation with the rear end of the spring check and release 66 for limiting the rearward movement of the clutch 62 within the taper 12. The slight shifting action, or backlash, of the clutch rearwardly of the taper 12 is sufficient to permit the gripping elements 88 to separate sufficiently far to permit the writing points 58 to pass freely through the opening 90 of the clutch 62 for lead propelling and repelling purposes.

The gripping elements 88 are so shaped as to separate when moved out of pressure relation with the tapered end 12, and the material of the clutch has sufficiently resilient properties to withstand the necessary flexing for gripping and releasing purposes. Since the fingers 64 extend into the path of the writing points 58, the writing points are prevented from falling through the released clutch 62 when the pencil is held in an upright position with the taper 12 pointing downwardly.

To propel the writing point 58 in the rear of the worn writing point 108, the clutch head 36 is separated from the coupling member 28 and the tubular part 18 pulled rearwardly to the position of Fig. 5. Upon disconnection of the clutch head 36 from the coupling member 28, the expanding tension of the gripping elements 88 effective against the taper 12 causes the clutch 62 to move rearwardly. Such rearward movement permits the gripping elements 88 to separate for enlarging the opening 90 to a degree which permits the writing points to pass freely therethrough.

In most cases, the tension of the gripping elements 88 is sufficient to shift the clutch rearwardly. In cases where the tension is insufficient or

the clutch should fail to automatically release for other reasons, a slight rearward pull on the member 18, after the clutch head 36 has engaged the collar 112 fixedly connected on the magazine 38, will exert a pull on the magazine 38 and shift the clutch 62 rearwardly of the tapered end 12.

Positive rearward shifting of the clutch 62 by manual force requires no separate act, and is consummated naturally by rearward shifting of the member 18 for moving the thrust arm 76 rearwardly for positioning the projector point 78 in the rear of the writing point 108 to be propelled. With the parts adjusted according to Fig. 5, the clutch head 36 is arranged in abutting relation with the collar 112. At this time, the end 105 of the spring check and release 66 has abutting relation with the coupling member 28, with the shoulders 114 of the clutch 62 arranged in spaced relation with the coupling member 28.

After the clutch head 36 has been moved into engagement with the collar 112, if the clutch 62 has not already released itself, the clutch may be pulled rearwardly a distance equal to the space between the rear end 105 of the spring check and release 66 and the coupling member 28 for shifting the clutch to a releasing position. Complete separation of the tube 22 from the outer tube 24 is prevented because of the abutting relation between the rear end 105 of the spring check and release 66 and the coupling member 28 when the tube 18 is pulled rearwardly.

In shifting the tubular member 18 to the position of Fig. 5, the thrust arm 76 is pulled rearwardly of the pencil to a position where the cam surface 110 upon the projector point 78 engages the end of the magazine 38 and cams the projector point 78 out of the path of the writing point to be advanced. In such position of the projector point 78, the lead to be advanced may drop freely into the expanded clutch.

Since the fingers 64 extend into the path of the writing points, the worn point 108 will be held by the fingers 64 in the open position of the clutch. The point to be propelled is prevented from falling out of the clutch because of its abutting relation with the worn point 108 when the pencil is held in an upright position with the taper 12 pointing downwardly.

With the writing point to be advanced lodged in the expanded clutch, the rear end of the writing point is in advance of the projector point 78 so as to be engaged thereby when the thrust arm 76 is pushed forwardly. A slight forward movement of the tubular part 18 brings the projector point 78 out of camming relation with the end of the magazine 38 so as to position the projector point 78 in abutting relation with the rear end of the writing point to be advanced. The new writing point is advanced easily since the resisting forces are limited to the tension of the fingers 64.

As the tubular part 18 is pushed toward the tubular part 28, the new writing point pushes the worn writing point 108 free of the gripping fingers 64, at which time the worn point is completely released from the pencil. In the releasing adjustment of the clutch 62, the pressure of the gripping elements 88 against the wall of the taper 12 constitutes a resisting force greater than the resisting forces between the gripping fingers 64 and the worn point so that the clutch will be held in its releasing position until the worn point has been pushed from the pencil and the new point moved to its proper position within the clutch to be clamped thereby. Because of the slight re-

sisting forces incident to the fingers 64, the worn point may be easily pushed out of holding relation with the fingers without damage to the point of the new writing point being advanced.

When the tubular member 18 has been pushed sufficiently far to advance the new writing point to its proper position within the clutch, the new writing point is prevented from being advanced a further distance through the abutting relation between the thrust collar 74 and the rear end of the clutch 62. After such abutment has been established, further advance of the tubular member 18 pushes the clutch inwardly of the tapered end 12 for pressing the gripping elements 88 into holding relation with the new writing point. Final forward adjustment of the tubular part 18 is determined by the threaded relation between the clutch head 36 and the coupling member 28. As the clutch head 36 is being screwed home, the clutch 62 is pressed firmly to its final position within the tapered end 12.

Referring to Fig. 4, the projector point 78 is arranged in abutting relation with the writing point projecting from the pencil so as to constitute an abutment capable of resisting forces applied to the writing point while in use. The abutting relation between the projector points 78 and the rear end of the writing points supplements the holding action of the gripping elements 88 upon the lead.

It will be noted that the projector arm 76 is positioned at all times within the race 96. In this way, the projector arm is restrained from relative rotary movement within the coupling member 28, which restraining movement is also effective with respect to the clutch 62 because of the relation between the flat surface 106 and the wall 94. The thrust collar 74 and the thrust arm 76 prevent the rotary movement of the clutch head from reaching the clutch. Thus, I prevent any relative rotary movement of the clutch. All adjustments of the clutch bodily are longitudinally of the pencil. In limiting the clutch to a shifting action longitudinally of the pencil, a durable construction is attained, one in which the gripping elements 88 are protected against distortion which would result if the clutch were rotated under pressure within the taper 12.

My pencil includes means for repelling the writing points. In repelling, the clutch head 36 is unscrewed from the coupling member 28 and the part 18 is shifted to the position of Fig. 5 with the tapered end 12 held upwardly.

Since the end 105 of the spring check and release 66 projects rearwardly beyond the shoulders 114 of the clutch 62, a further pull on the member 18 with the clutch head 36 in abutting relation with the collar 112, and the end 105 of the spring check and release 66 in abutting relation with the coupling member 28, will pull the clutch 62 rearwardly between the plates 82 until the shoulders 114 have engaged the wall 94. Fig. 6 illustrates such adjustment of the parts.

The shoulders 102 define obtuse angles with respect to the flattened faces 84 so that the ends 103 of the plates 82 will have camming relation therewith for imparting a separating action to the plates 82. Such separation of the plates 82 causes the fingers 64 to separate sufficiently far to release the writing point in the clutch 62. With the clutch 62 and the spring check and release 66 adjusted according to Fig. 6, the angular reaches 116 of the plates 82 will lie on the

ledges 118 formed on the clutch 62. The increased spring tension incident to separation of the plates 82 will cause the reaches 116 to have sufficient frictional relation with the ledge 118 5 to hold the parts adjusted according to Fig. 6.

With the pencil adjusted to its repelling position, the lead magazine 38 is clear of any and all mechanical obstructions. In case of accidental jamming or clogging of the magazine 38, 10 the magazine may be cleaned by a suitable instrument with no danger of damaging mechanical parts which in other adjustments project into the path of the writing points.

As the clutch is pulled backward into the 15 spring check and release 66, the shoulders 114 on the clutch 62 are brought into abutting relation with the wall 94, which prevents further separation of the plates 82. With the pencil held with the tapered point 12 pointing upward, 20 and the fingers 64 separated, the writing point in the clutch 62 will drop of its own weight to a position within the magazine 38 entirely within the clear of the outer end of the taper 12. The repelled writing point falls to a position in the 25 rear of the projector point 78 so as not to be propelled when the pencil is adjusted to its normal condition for carrying purposes.

After repelling, the pencil is adjusted to its 30 normal condition by advancing the tubular member 18 together with the clutch head 36 and the thrust collar 74 until the thrust collar 74 comes into abutment with the rear end of the clutch 62 and pushes it forward into the tapered end 12. This action brings the angular reaches 116 35 of the plates 82 into abutment with the inner face of the tapered end 12. Continued forward movement of the clutch after such abutting relation has been established pushes the angular reaches 116 off the ledges 118 so that the plates 40 82 will resume their normal relation with respect to the flat faces 84.

In operating the pencil for propelling and expelling purposes, there is no danger of accidentally shifting the parts to the repelling adjustment, as a very much greater force is required to draw the tubular part 18 to the repelling position than is required for merely shifting the part to its propelling and expelling position. This is due to the pressure of the plates 82 against the 50 flat sides 84 of the clutch 62 and the additional resistance between the ends 103 and the camming shoulders 102. The operator, in drawing back the tubular member 18, quickly learns to distinguish between the first degree of resistance 55 caused by the abutting relation between the rear end of the spring check and release 66 and the wall 94 for propelling and expelling purposes, and the second degree of resistance caused by the abutting relation between the shoulders 114 of 60 the clutch 62 and the wall 94.

In the act of repelling, the rear part of the magazine 38 is lengthened by the tubular support 48 as it is drawn back with the tubular part 18. This is a very desirable feature when the 65 magazine 38 is filled to capacity with writing points, as it permits all writing points to shift back far enough to make room for the writing point being repelled to fall behind the projector point 78 so as not to be propelled into the clutch 70 when the pencil is adjusted to its normal position. After repelling and adjustment of the pencil to its normal position, the fingers 64 and the projector point 78 prevent the writing points from protruding or falling out of tapered end 12.

75 In the normal position of the pencil, the pin

52 projects into the magazine 38. This pin performs a protective function for the rearmost writing point during the repelling adjustment of the pencil. The pin projects inwardly of the magazine and constitutes an abutment for the rearmost writing point when the writing points are shifted rearwardly for repelling purposes so as to prevent the rearmost writing point from dropping entirely clear of the magazine 38.

10 After repelling, the pin 52 engages the rearmost writing point and pushes all the writing points inwardly of the magazine. In functioning as an abutment that permits the rearmost writing point to only partially leave the magazine 38, the pin 52 prevents any breaking of the rearmost writing point which might occur if the writing point moved completely out of the magazine into the tubular support 48. In Fig. 2, I illustrate the rear end of the magazine 38 as being counterbored at 120, facilitating loading of the 15 magazine 38 with a supply of writing points 58.

15 My pencil embodies a simple construction whereby new writing points 58 may be easily and quickly substituted for the worn points. A large supply of these points may be carried in 20 the magazine 38, and the construction is such that a new writing point may be easily substituted by simple manipulation of the parts.

25 Without further elaboration, the foregoing will 30 so fully explain my invention that others may, by applying current knowledge, readily adapt the same for use under various conditions of service.

I claim:

1. A pencil comprising a barrel having a tapered end and an actuating part, a magazine 35 housed within the barrel for containing a plurality of sharpened leads, a lead gripping clutch positioned within the tapered end of the barrel and having pressure relation therewith for moving the clutch into clamping relation with the 40 propelled lead, and an operating connection between the actuating part and said clutch for moving the same into and out of pressure relation with the tapered end.

2. A pencil comprising a barrel having a tapered end and an actuating part, a magazine housed within the barrel for containing a plurality of sharpened leads, a lead gripping clutch positioned within the tapered end of the barrel and having pressure relation therewith for moving the clutch into clamping relation with the 50 propelled lead, an operating connection between the actuating part and said clutch for moving the same into and out of pressure relation with the tapered end, and means associated with the clutch 55 for releasably holding the propelled lead in the lead releasing adjustment of the clutch.

3. A pencil comprising a barrel having a tapered end and an actuating part, a magazine housed within the barrel for containing a plurality of sharpened leads, a lead gripping clutch positioned within the tapered end of the barrel and having pressure relation therewith for moving the clutch into clamping relation with the 60 propelled lead, an operating connection between the actuating part and said clutch for moving the same into and out of pressure relation with the tapered end, means associated with the clutch for releasably holding the propelled lead in the lead releasing adjustment of the clutch, 65 and means for rendering the holding action of said means inoperative.

4. A pencil comprising a barrel having a tapered end and an actuating part, a magazine housed within the barrel for containing a plu- 70 75

rality of sharpened leads, a lead gripping clutch positioned within the tapered end of the barrel and having pressure relation therewith for moving the clutch into clamping relation with the 5 propelled lead, said clutch being fixedly connected with the magazine and being arranged to receive leads therefrom, and an operating connection between the actuating part and said magazine for moving the clutch into and out of pressure 10 relation with the tapered end.

5. A pencil comprising a barrel having a tapered end and an actuating part, a magazine housed within the barrel for containing a plurality of sharpened leads, a lead gripping clutch positioned within the tapered end of the barrel and having pressure relation therewith for moving the clutch into clamping relation with the propelled lead, said clutch being fixedly connected with the magazine and being arranged to receive 15 leads therefrom, an operating connection between the actuating part and said magazine for moving the clutch into and out of pressure relation with the tapered end, and means associated with the clutch for releasably holding the propelled lead 20 in the lead releasing adjustment of the clutch.

6. A pencil comprising a barrel having a tapered end and an actuating part, a magazine housed within the barrel for containing a plurality of sharpened leads, a lead gripping clutch positioned within the tapered end of the barrel and having pressure relation therewith for moving the clutch into clamping relation with the propelled lead, said clutch being fixedly connected with the magazine and being arranged to receive 25 leads therefrom, an operating connection between the actuating part and said magazine for moving the clutch into and out of pressure relation with the tapered end, and means associated with the clutch for releasably holding the propelled lead in the lead releasing adjustment of the clutch, and means for rendering the holding action of said means inoperative.

7. A pencil comprising a barrel having a tapered end and an actuating part, a magazine housed within the barrel for containing a plurality of sharpened leads, a clutch including resilient elements positioned within the tapered end of the barrel and having pressure relation therewith for moving the gripping elements into 30 clamping relation with the propelled lead, said gripping elements being spaced, resilient means associated with the clutch and positioned between some of the gripping elements for releasably holding the propelled lead with the clutch shifted to its releasing position, and an operating connection between the actuating part and said clutch for moving the same into and out of pressure 35 relation with the tapered end.

8. A pencil comprising a barrel having a tapered end and an actuating part, a magazine housed within the barrel for containing a plurality of sharpened leads, a clutch fixedly connected with said magazine and including gripping elements having pressure relation with the 40 tapered end for moving the gripping elements into clamping relation with the propelled lead, means for restraining rotary movement of the clutch relatively to the tapered end, an operating connection between the actuating part and said clutch, said gripping elements being spaced apart, and resilient fingers carried by the clutch and positioned between some of the gripping elements for releasably supporting the propelled in the releasing position of the clutch.

75 9. A pencil comprising a barrel having a ta-

pered end and an actuating part, a magazine housed within the barrel for containing a plurality of sharpened leads, a lead gripping clutch positioned within the tapered end of the barrel and having pressure relation therewith for moving the clutch into clamping relation with the 5 propelled lead, an operating connection between the actuating part and said clutch for moving the same into and out of pressure relation with the tapered end, and a projector arm connected with said connection for advancing a lead into 10 the clutch.

10. A pencil comprising a barrel having a tapered end and an actuating part, a magazine housed within the barrel for containing a plurality of sharpened leads, a lead gripping clutch positioned within the tapered end of the barrel and having pressure relation therewith for moving the clutch into clamping relation with the 15 propelled lead, an operating connection between the actuating part and said clutch for moving the same into and out of pressure relation with the tapered end, a projector arm connected with said connection for advancing a lead into 20 the clutch, and means for moving the projector arm 25 out of the path of an advancing lead.

11. A pencil comprising a barrel having a tapered end and an actuating part, a magazine housed within the barrel for containing a plurality of sharpened leads, a clutch fixedly connected with one end of the magazine, said clutch including resilient elements positioned within the tapered end of the barrel and having pressure relation therewith for moving the gripping elements into clamping relation with the propelled lead, said gripping elements being spaced apart, a spring check and release movably related to the clutch and having fingers positioned between some of the spaces between the gripping elements for holding a lead positioned between the latter, an abutment positioned within the barrel, cam means carried by the clutch for separating said fingers, and an operating connection between 30 said actuating part and the magazine for moving the clutch out of pressure relation with the tapered end, said spring check and release being arranged to engage said abutment for moving the same into engagement with said cam means, to separate the fingers.

12. A pencil comprising a barrel having a tapered end and an actuating part, a magazine housed within the barrel for containing a plurality of sharpened leads, a clutch including resilient elements positioned within the tapered end of the barrel and having pressure relation therewith for moving the gripping elements into clamping relation with the propelled lead, said gripping elements being spaced apart, a spring check and release movably related to the clutch and having fingers positioned between some of the spaces between the gripping elements for holding a lead positioned between the latter, an abutment positioned within the barrel, cam means carried by the clutch for separating said fingers, an operating connection between said actuating part and the magazine for moving the clutch out of pressure relation with the tapered end, said spring check and release being arranged to engage said abutment for moving the same into engagement with said cam means, to separate the fingers, a projector arm connected with the magazine for movement therewith, said projector arm being arranged to engage the inner end of the lead positioned in the clutch, 50 55 60 65 70 75

and means for camming the projector arm out of the path of the leads in the magazine.

13. A pencil comprising a two part barrel having an operating connection permitting separation of the parts, one of the parts including a tapered end, a lead gripping clutch positioned within the tapered end of the barrel and having pressure relation therewith for moving the clutch into clamping relation with the propelled lead,
10 a magazine housed within the barrel for containing a plurality of sharpened leads, said magazine being fixedly connected with the clutch and arranged to deliver leads thereto, a clutch head slidably mounted on said magazine and fixedly
15 connected with said operating connection, a projector arm loosely connected with said clutch head for pushing a lead into said clutch, said projector arm having a part normally positioned within said magazine, and means for camming
20 the projector arm to the clear of the magazine when said parts are separated.
14. A pencil comprising a two part barrel having an operating connection permitting separation of the parts, one of the parts including a
25 tapered end, a lead gripping clutch positioned within the tapered end of the barrel and having pressure relation therewith for moving the clutch into clamping relation with the propelled lead, a magazine housed within the barrel for containing a plurality of sharpened leads, said magazine being fixedly connected with the clutch and arranged to deliver leads thereto, a clutch head slidably mounted on said magazine and

fixedly connected with said operating connection, a projector arm movably connected with said clutch head for pushing a lead into said clutch, said projector arm having a part normally positioned within said magazine, means for camming the projector arm to the clear of the magazine when said parts are separated, a spring check and release carried by said clutch, said spring check and release including resilient elements arranged to hold the lead in the clutch in the releasing position of the clutch, and means for shifting the fingers to a releasing position upon a predetermined degree of separation of said parts. 10

15. A pencil comprising a barrel having a tapered end and an actuating part, a magazine housed within the barrel for containing a plurality of sharpened leads, a lead gripping clutch positioned within the tapered end of the barrel and having pressure relation therewith for moving the clutch into clamping relation with the propelled lead, said clutch being fixedly connected with the magazine and being arranged to receive leads therefrom, an operating connection between the actuating part and said magazine for moving the clutch into and out of pressure relation with the tapered end, means associated with the clutch for releasably holding the propelled lead in the lead releasing adjustment of the clutch, and means for moving the last named means into non-holding relation with the lead. 20 25 30

JOHN A. LEIMER.
